UNITED STATES PATENT OFFICE.

LEO KRAUSE, OF NEW YORK, N. Y.

BULLETPROOF ARMOR.

Application filed February 10, 1923. Serial No. 618,229.

To all whom it may concern:

Be it known that I, LEO KRAUSE, a citizen of the United States, residing at New York, in the county of New York and State of New York, have invented new and useful Improvements in Bulletproof Armor, of which the following is a specification.

This invention relates to a bullet proof armor which is particularly adapted for 10 policemen when called to quell a riot or by soldiers in battle to protect vital parts of the body.

The invention is designed to provide a shield for the body which can be worn under 15 the clothing and by its lightness in weight prevent any discomfort and at the same time effectively protect the body from injury by the impact of a missile.

An object of the invention is to provide 20 intermediate tenacious metal plates composed of a light metal of sufficient strength to resist the impact of a bullet. The metal is covered with a metallized fibre so that the heat from a bullet cannot set it on fire 25 or moisture rust the plates.

Another object of the invention is to arrange a quilted buffer between the metallized fibre and the plates whereby the force of the missile is considerably lessened before 30 it impinges on the plate.

The invention resides more particularly in the novel combination hereinafter described and claimed, reference being made to the accompanying drawing in which:

35 Figure 1 represents a front elevation of a shield embodying this invention.

Figure 2 is a vertical longitudinal section of the same.

Figure 3 is a perspective view of a portion 40 of the quilt.

In the drawing the numeral 5 designates a series of metal plates made of duralumin each plate being enclosed in a pocket 6 of fabric. The pockets partly overlap each 45 other to produce a shingle formation and each pocket is fastened at its upper end by means of stitches 7 to a piece of fabric 8 located at the back of the pockets.

Arranged at the front of the pockets is a 50 quilted member built up of a stuffing of raw China silk 9 covered with a metallized fabric 10 secured together by stitches 11 as indicated in Figure 3. A similar quilt 12 is located at the back of the fabric 8. On

each quilt is secured by means of stitches 55 13 a sheet of metallized fibre 14 and a pair of shoulder straps 15 support the shield on the body.

In the drawing the invention is shown applied to a shield adapted to be worn under 60 a coat but it will be obvious that it could be utilized for other purposes such as a cover for the actuating parts of an aeroplane thus protecting it against gunshot.

The metallized fibre placed on the outside 65 of the quilt is practically fire and waterproof consequently a bullet fired from a gun at close range will not inflame the fibre nor will any moisture have any effect on it. The stuffing is preferably composed of China 70 silk which by its toughness and close compression will retard a missile. A bullet fired at great velocity will merely embed itself in the metal aluminum and if it should go through it will be stopped by the quilt behind the plates. The duralumin is used in the present device because it is much lighter than any other metal so as not to add any undue weight to the shield member.

I claim:

1. A bullet proof armor comprising a shield constructed of a series of tenacious metal plates lighter than steel, and a quilted member arranged adjacent to the plates.

2. A bullet proof armor comprising a shield constructed of a series of metal plates, and a quilted member covering the plates.

3. A bullet proof armor comprising a shield constructed of a series of metal plates, a pocket enclosing each plate and a quilted member arranged adjacent to each pocket.

4. A bullet proof armor comprising a shield constructed of a series of metal plates, partly overlapping each other, a pocket enclosing each plate, and a quilted member covering the front and back of the pockets.

5. A bullet proof armor comprising a shield constructed of a series of metal plates, a pocket enclosing each plate, a quilted member arranged adjacent to the plates, and a metallized fibre sheet secured to the quilt.

6. A bullet proof armor comprising a shield constructed of a series of duralumin plates, a pocket enclosing each plate, a quilted member having a stuffing of raw China silk arranged adjacent to the plates, and a metallized fibre sheet secured to the quilt.

7. A bullet proof armor comprising a

shield constructed of a series of intermediate metal plates one partly overlapping the other, a pocket enclosing each plate, a quilted member arranged at the front and 5 back of the pockets, each member having a stuffing of raw China silk, and a metallized fibre sheet secured to the outer side of each quilt.

In testimony whereof I have hereunto set my hand in the presence of two subscribing 10 witnesses.

LEO KRAUSE.
